(57) **CLAIM**

I claim the ornamental design for a brassiere with pockets, as shown and described.

DESCRIPTION

FIG. 1 is a front elevational view of a brassiere with pockets, showing my new design, shown with the back lateral fastener in the opened condition, shown with the left brassiere cup's fastener in the closed condition and the right brassiere cup's fastener in the opened condition;

FIG. 2 is a top plan view thereof;

FIG. 3 is a right side elevational view thereof, shown with the back lateral fastener in the closed condition, shown with the right brassiere cup's fastener in the opened condition;

FIG. 4 is a left side elevational view thereof, shown with the back lateral fastener in the closed condition, shown with the left brassiere cup's fastener in the closed condition;

FIG. 5 is a bottom plan view thereof, shown with the back lateral fastener in the opened condition;

FIG. 6 is a front elevational view thereof, shown with the back lateral fastener in the closed condition, shown with the left brassiere cup's fastener in the closed condition and the right brassiere cup's fastener in the opened condition; and,

FIG. 7 is a rear elevational view thereof, shown with the back lateral fastener in the closed condition.

The dashed lines shown in the drawings represents a stitching line.
